(57) **CLAIM**

The ornamental design for a firearm slide, as shown and described.

DESCRIPTION

FIG. 1 is a perspective view of a firearm slide showing our new design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top elevation view thereof; and,

FIG. 7 is a bottom elevation view thereof.

The broken lines in the figures are for the purpose of illustrating environmental structure only and form no part of the claimed design. Any surface or portion of our design not shown in the figures or otherwise described herein forms no part of the claimed design.

1 Claim, 5 Drawing Sheets
